United States Patent Office

Des. 185,780
Patented Aug. 4, 1959

185,780

MIXER OR THE LIKE

Earl S. Tupper, Smithfield, R.I., assignor to Tupper Corporation, North Smithfield, R.I., a corporation of Delaware

Application June 10, 1957, Serial No. 46,534

Term of patent 14 years

(Cl. D2—3)

Fig. 1

Fig. 2

Figure 1 is a perspective view of a mixer or the like embodying my new design;

I claim:

The ornamental design for a mixer or the like, substantially as shown.
